UNITED STATES PATENT OFFICE.

MANIOUS GARL, OF AKRON, OHIO.

ELECTRIC FIRE-ALARM SYSTEM.

SPECIFICATION forming part of Letters Patent No. 641,950, dated January 23, 1900.

Application filed September 12, 1899. Serial No. 730,269. (No model.)

To all whom it may concern:

Be it known that I, MANIOUS GARL, a citizen of the United States, residing at Akron, in the county of Summit and State of Ohio, 5 have invented new and useful Improvements in Electric Fire-Alarm Systems, of which the following is a specification.

My invention relates to electric fire-alarm systems, the same being particularly adapted 10 for use in hotels, warehouses, and the like, the object of the invention being to provide an automatic protective system by means of which an alarm will be given in case of fire at a point near the conflagration and also at 15 a central office or station and in which an alarm may be sent to all parts of the house from the central office or station.

A further object of the invention is to provide an improved construction of signaling 20 device to be used on the system by means of which an alarm loud enough to awaken the soundest sleeper may be given.

Other objects and advantages of the invention will hereinafter appear, and the novel 25 features thereof will be set forth in the claims.

In the drawings forming part of this specification, Figure 1 is a diagrammatic view illustrative of my improved system. Fig. 2 is a top plan view, partly broken away, of the 30 switch-box. Fig. 3 is a bottom plan view of the same.

Like reference-numerals indicate like parts in the different views.

The system as a whole is illustrated in Fig. 35 1 of the drawings, in which 1 and 2 indicate two of a series of signaling devices located in different rooms, in the hallways, or at other convenient points of the hotel or other building to be protected, the same being connected 40 through the wires 3 and 4, respectively, with the general return-wire 5, leading to one pole of the battery 6. The signaling device 7, similar in all respects to the signaling devices 1 and 2, is located in the central station or 45 office of the hotel, the same being connected through the wire 8 with the other pole of the battery 6. From the device 7 leads the wire 9, connected through the wires 10, 11, and 12 with the thermostatic circuit-closers 13, 14, 50 and 15, respectively, and through the wires 16, 17, and 18 with the thermostatic circuit- 16, 17, and 18 with the thermostatic circuit-

closers 19, 20, and 21. The said circuit-closers are arranged in multiple, as shown, and are connected through the wires 22, 23, 24, and 25 and 26, 27, 28, and 29 with the signaling 55 devices 1 and 2 on the side opposite that from which the wires 3 and 4, heretofore referred to, lead. The circuits from the battery 6 through the signaling devices 1, 2, and 7 are normally open, but are adapted to be closed 60 by means of the thermostatic circuit-closers referred to, and when closed through any one of these devices the signaling device 7 is placed in series with the signaling device 1 and 2, which is controlled by the circuit-closer 65 which has been actuated. Say, for example, that the circuit is closed through the circuit-closer 13, the flow of current will then be from battery 6 through wire 8 to signaling device 7, actuating the latter, and thence through 70 wires 9 and 10, circuit-closer 13, wires 24 25, signaling device 1, and wires 3 and 5 to battery. A signal will thus be given by both of the devices 1 and 7, notifying the office of the hotel and the occupants of the building adjacent to 75 the point of conflagration. The same result will take place if any one of the other circuit-closers connected with the signaling device 1 be actuated. The same result will also take place, except that the signaling device 2 will 80 be actuated, if the circuit be closed through any one of the circuit-closers 19, 20, or 21. Push-buttons 30 31 are provided, preferably inclosed in glass cases and in multiple through the wires 32 33 and 34 35, with the circuit- 85 closers connected, respectively, with the signaling devices 1 and 2. Through these push-buttons the circuit through the signaling devices 1 and 7 or 2 and 7 may be closed by hand. In this way the alarm may be given manually 90 in case the automatic circuit-closers fail to act or in the event that it is desired to test the circuits. Also located in the central station or office of the hotel is a switch-box 36, having a plurality of binding - posts 37 37 thereon, 95 which constitute the terminals of circuits through the wires 38 and 39 from the signaling devices 1 and 2, respectively. These binding-posts are mounted upon a disk or plate 40, of insulating material, extend therethrough, 100 and are provided with contacts 41 on the under side of said disk. These contacts are

adapted to be engaged by a rotatable arm 42, mounted upon a spindle or arbor 43, which arm is electrically connected with one pole of the battery 6 through the wire 44. The spindle or arbor is adapted to be rotated by a coil-spring 45, and the mechanism of the switch includes a system of gearing with which operates an escapement 46, having an arm 47 thereon. The normal tendency of the spring 45 is to rotate the spindle or arbor 43 and carry the arm 42 around, so that it makes contact in succession with each one of the contact-points 41 on the under side of the binding-posts 37. This spring is controlled and 15 the arm 42 is held locked in any position by means of a lever 48, fulcrumed upon the under side of the base of the switch-box 36 and having an upwardly-extending pin or arm 49 projecting through a segmental slot 50 in said 20 base and adapted to engage the arm 47 of the escapement 46. It will be seen that as the points of pivotal connection between the arm 47 and the switch-box and between the lever 48 and the switch-box are out of alignment 25 with each other when the lever 48 is moved so as to bring the pin 49 thereon into engagement with the arm 47 said escapement will be locked against rocking movement, and as this escapement controls the gearing between 30 it and the spindle or arbor 43 said spindle or arbor and the arm 42, carried thereby, will be locked in any position to which it may have been moved. By moving the lever 48 in the opposite direction, so as to throw the pin 49 35 out of contact with the arm 47, the escapement 46 is free to rock, and the spring 45 is thereby free to actuate the spindle which carries the arm 42. As shown in Fig. 1 of the drawings, the arm 42 is locked at a point between two of the contact-pieces 41, and no 40 current can flow therefore through either one of the wires 38 or 39. If after an alarm has been sent to the central station or office in the hotel, however, it is desired to give the alarm 45 throughout the building, it is merely necessary to move the lever 48 so as to release the escapement 46, when the spring 45 will cause the rotation of the spindle 43 and the arm 42, carried thereby. This arm during this rotation 50 makes contact with each one of the contact-points 41 at the lower ends of the binding-posts 37. The result is that an alarm is sent to each one of the signaling devices 1 and 2 throughout the building protected. When, 55 for example, the arm 42 is in contact with the contact-point 41, which constitutes the terminal of the circuit through the wire 38, the flow of current will be from battery 6 through wire 44, arm 42, contact-point 41, wires 38 and 25, 60 to signaling device 1 and back to the battery through the wires 3 and 5. The signaling device 1 will therefore be actuated and the alarm given thereby. A similar operation with respect to the signaling device 2 will be effected 65 when the arm 42 is in contact with the contact-point 41, which constitutes the terminal of the circuit through the wire 39.

The use of bells as fire-alarm signaling devices has proved totally ineffective and unsatisfactory, for the reason that the sound produced thereby is not loud or penetrating enough to awaken many sleepers and is so common, particularly in large cities, that even when it is heard it is unheeded. I have provided an improved construction of signaling device by means of which a blank cartridge of suitable size may be fired for the purpose of giving an alarm of fire. This is much more effective in actual use than the ordinary bell in that the sound produced thereby is louder 70 and more penetrating and in that it is more certain to rouse a sleeping person by reason of the fact that it is of an unusual character. The same consists of a pendant 51, secured to the ceiling or other convenient place, comprising a shell or casing 52, of wood or other insulating material, and a depending cylindrical tube 53, having an internal annular flange 54 at a point adjacent to its lower end and internal screw-threads just below the 80 flange 54. Adapted to screw into the lower end of the tube 53 is a plug 55, having a central cylindrical aperture 56 therein, provided for the reception of a blank cartridge. Secured to the lower end of the plug 55 is a guard 85 57, preferably made from a strip of sheet metal bent into U shape, with its ends secured to the opposite sides of said plug. This guard serves to prevent the wad which retains the charge of powder in the cartridge from 90 being projected downwardly with force sufficient to injure a person who might be struck thereby. The open sides of the guard, however, provide for the escape of the gases generated. The cartridge is placed in the plug 100 55 with its base uppermost, and the same is fired by means of an exploder 58, consisting of a heavy cylindrical bar having an external annular flange or shoulder 59 thereon, which is adapted to engage the internal annular 105 flange 54 on the tube 53 for limiting its downward movement, and provided with a pointed projection or firing-pin 60, which when said exploder is dropped engages the cap of the cartridge in the plug 55 and fires the same. 110 The exploder 58 is retained normally in its raised position by the engagement of a flange or shoulder 61 thereon with the armature 62 of an electromagnet 63. Said armature is pivoted along its lower edge and is normally held 115 away from the poles of the magnet 63 by means of springs 64, of copper or other non-magnetic material, which are secured to said armature and engage the poles of said magnet. When the magnet is energized by the passage of an 120 electric current through the coils thereof, the armature 62 is drawn toward said magnet and away from the exploder 58. Said exploder then drops by gravity and fires the cartridge 125 in the plug 55 in the manner heretofore described. 130

From the foregoing description it will be observed that I have devised an extremely simple and effective automatic fire-alarm sys-

tem and also an extremely effective signaling device to be used in connection therewith, by means of which an alarm which will be effective is rousing the soundest sleeper may be given. In Fig. 1, illustrating the system, I have shown but two of these signaling devices in the building which is to be protected; but it is obvious that any number might be employed. I have also illustrated and described certain details of construction; but I do not limit myself to any of these details, except as is set forth in the claims.

Having now described my invention, what I claim as new, and desire to secure by Letters 15 Patent, is—

1. In an electric fire-alarm system, a signaling device at a central station, and a plurality of the same at distances therefrom, a battery, circuit connections between the distant signaling devices and one side of said battery, circuit connections between each of the distant signaling devices, the signaling device at the central station, and the other side of said battery, and circuit-controlling means 20 for throwing into operation each of the distant signaling devices and simultaneously placing the signaling device at the central station in series therewith, whereby the signaling device at the central station and the 25 distant signaling device which has been thrown into operation will be actuated simultaneously.

2. In an electric fire-alarm system, a signaling device at a central station and a plurality 30 of the same at distances therefrom, a battery, a general return-wire connected with one side of each of the distant signaling devices and with one pole of said battery, circuit connections between each of the distant signaling 35 devices, the signaling device at the central station and the other side of said battery, and a plurality of thermostatic circuit-controllers for each of the distant signaling devices, the said circuit-controllers being in multiple with 40 each other and adapted to throw into operation one or the other of said distant signaling devices and to place in series therewith the signaling device of the central station, whereby the signaling device at the central station 45 and the distant signaling device which has been thrown into operation will be actuated simultaneously.

3. In an electric fire-alarm system, a signaling device at a central station and a plurality 50 of the same at distances therefrom, a battery, circuit connections between said battery and said signaling devices, circuit-controlling means for placing one of the distant signaling devices in series with the signaling device 55 of the central station and for actuating both simultaneously, and circuit-controlling means at the central station for throwing the distant signaling devices into operation.

4. In an electric fire-alarm system, the combination with a signaling device at a central 60 station and a plurality of the same at distances therefrom, a battery, circuit connec-

tions between the distant signaling devices and one side of said battery, circuit connections between each of the distant signaling devices and the other side of said battery through the signaling device at the central station, circuit-controllers for each of the distant signaling devices for throwing into operation the distant signaling devices, coupling in series 70 therewith the signaling device at the central station and thereby actuating both of said signaling devices simultaneously, of a switch, contact-points thereon forming the terminals of circuits leading from the distant signaling 75 devices, and a rotatable arm connected with said battery and adapted to engage each of the contact-points on said switch, as and for the purpose set forth.

5. In an electric fire-alarm system, a signaling device comprising a cartridge-holder, a gravity-actuated exploder therefor, having a shoulder thereon, an electromagnet and an armature for said magnet lying within the path of movement of said exploder and adapted 80 to engage said shoulder for retaining said exploder in raised position and to be released therefrom by said magnet.

6. In an electric fire-alarm system, a signaling device consisting of a pendant having a 85 casing and a cylindrical extension thereon, a cartridge-holding plug fitting the lower end of said extension, a gravity-actuated exploder for the cartridge movable in said tubular extension, means for retaining said exploder in raised position and an electromagnet 90 in said casing for releasing said exploder.

7. In an electric fire-alarm system, a signaling device consisting of a pendant having a 95 casing and a cylindrical extension thereon, a cartridge-holding plug fitting the lower end of said extension, a gravity-actuated exploder for the cartridge movable in said tubular extension, and having a flange or shoulder 100 thereon, an electromagnet in said casing and an armature therefor adapted to engage said shoulder for retaining said exploder in its raised position and adapted to be released by said magnet.

8. In an electric fire-alarm system, a signaling device consisting of a pendant having a 105 casing and a cylindrical extension thereon, a cartridge-holding plug fitting the lower end of said extension, a guard on said plug, an exploder for the cartridge, and means controlled 110 by an electromagnet for throwing said exploder into operation.

9. In an electric fire-alarm system, a plurality of signaling devices, a battery, circuit 115 connections between said signaling devices and one side of said battery, a switch-box, contact-points thereon, circuit connections between said signaling devices and said contact-points, a traveling arm electrically connected with the other side of said battery and adapted to engage each of said contacts, a 120 motor for rotating said arm including a system of gearing, and a vibrating escapement 130

having an arm thereon, and a lever ful-
crumed to the switch-box and having a pin
or projection thereon adapted to engage the
arm on said escapement whereby said motor
5 may be controlled, as and for the purpose set
forth.

In testimony whereof I have hereunto set

my hand in presence of two subscribing wit-
nesses.

MANIOUS GARL.
